UNITED STATES PATENT OFFICE.

FLORENCE BAXTER, OF PASSAIC, NEW JERSEY.

DESIGN FOR A TEA-CUP.

40,365.

Specification for Design.

Patented Nov. 23, 1909.

Application filed August 31, 1909. Serial No. 515,548. Term of patent 3½ years.

To all whom it may concern:

Be it known that I, FLORENCE BAXTER, a citizen of the United States, residing in Passaic, in the county of Passaic and State of New Jersey, have invented a new, original, and ornamental Design for Tea-Cups, of which the following is a specification, reference being had to the accompanying drawing, forming part thereof, which shows a plan or top view of my design.

I claim:

The ornamental design for a tea-cup as shown.

FLORENCE BAXTER.
